AUTOMATIC RECLINING CHAIR

Homer E. Smith, Toledo, Ohio

Application December 31, 1934, Serial No. 759,950

8 Claims. (Cl. 155—55)

This invention relates to new and useful improvements in automatic reclining chairs.

It is one of the principal objects of my invention to provide an automatic, reclining chair that is full floating on the yielding means in any of its positions to afford complete rest and relaxation to the occupant. The chair is so constructed that the one occupying it has no feeling of sitting or lying on anything solid, while a pleasant swinging motion follows any movement of the body to add to one's rest and comfort in a reclining as well as in an upright position.

My chair lends itself for use as a shock absorbing seat for railway cars and busses, and may be employed as an ideal ambulance cot or seat.

Other important and incidental objects will be brought out in the following specification, and particularly set forth in the subjoined claims.

In the accompanying drawings illustrating my invention, Figure 1 is a perspective view of my automatic, reclining chair in an upright position. Figure 2 is a front elevational view of said chair and a foot rest which may be used with it. Figure 3 is a side elevational view thereof. Figure 4 is a front view of one form of spring mechanism for floatingly supporting the chair seat and back. Figure 5 is a cross-sectional view taken on the line 5—5 of Figure 4. Figure 6 is a longitudinal, sectional view taken through the spring mechanism on the line 6—6 of Figure 4. Figure 7 is a perspective view of my chair, showing a heavy person in a reclining position therein. Figure 8 is a similar view of my chair when supporting a person approximately fifty pounds lighter than the occupant shown in Figure 7. And Figure 9 is a side view of one of the coil type of springs used in my chair as illustrated in Figures 7 and 8.

Referring to the accompanying drawings for a detailed description of my invention, the numerals 1, 1 designate the front legs, and 2, 2 the rear curved legs of my reclining chair. The numerals 3, 3 designate base rails which are connected by cross rails 4, 4. The upper ends of the legs 2, 2 are connected by cross rails 4^a, 4^a, just behind the point where these legs join the upper portions of the front legs 1, 1. The curved legs 2, 2 which project upwardly and forwardly from the rear part of the base frame formed by the side rails 3, 3 and the cross rails 4, 4, brace the vertical front legs 1, 1.

Pivots secured to the upper ends of the legs 1, 1 are the front ends of horizontal seat members 5, 5. To the rear ends of the latter back members 6, 6 are pivotally attached. Pivots secured to the lower portions of these back members are the rear ends of arms 7, 7 that are pivotally joined at their front ends to vertical lever members 8, 8. These members project downwardly through slots in the seat members 5, 5,

to which they are fulcrumed at their middle portions by means of fulcrum pins 8^a, 8^a, for an oscillating or swinging movement.

For the purpose of floatingly supporting the chair seat and back in an upright or desired inclined position, I provide a yielding connection between a fixed member on the chair base, and the lower ends of the swinging members 8, 8. In Figures 4 and 5 this yielding connection takes the form of an adjustable coil spring structure 10 which will now be described. Secured to supporting blocks 9, 9 attached to the legs 2, 2 a short distance behind the swinging members 8, 8 when they are in an upright position, are the ends of a fixed horizontal rod 10.

Secured to the lower free ends of the oscillatory member 8, 8 are the ends 11 and 11^a of a floating tubular member 12 that is parallel with the fixed rod 10.

Coil springs 43 are directly connected between the fixed rod 10 and the floating tubular member 12 to yieldingly support the occupant in an upright state, or in any desired reclining position.

In my construction the same spring 43 that sustains the seat, also controls the reclining back. Because of this construction the force exerted against the back is directly proportional to the weight of the occupant, and is balanced at all points. When the occupant reclines the force exerted against the back increases as the weight is transferred from the seat to the back, causing the resistance of the springs 43 to increase.

During the reclining movement of the occupant's body, his feet are not lifted from the floor because the point *a* in Figure 3 does not change. However, the points of attachment of the seat members 5, 5 to the legs 1, 1 follow the natural action of the hip joints to accommodate the chair to the occupant's body in all of its positions, thus insuring complete rest and relaxation to the person using the chair.

In Figures 4, 5 and 6 I have shown an alternative spring construction from that illustrated in Figures 1, 2, 3, 7, 8 and 9. This modification will now be described.

Pivots mounted on the middle portion of the fixed rod 10 is a T-shaped supporting member 13. Formed at the middle and each end of the cross portion 14 of this T-member is a boss 15 provided with an axial hole through which the rod 10 projects to support said T-shaped member for an oscillatory movement. The vertical part 16 of the T-shaped member 13 terminates at its lower end in a yoke 17 which straddles the floating member 12. (See Figures 4 and 5).

The vertical portion 16 of the T-member 13 is enlarged a short distance above its yoke end 17 to provide a reinforced axial hole 18 to receive a horizontal spring-supporting rod 19 which is

slidable and rotatable therein. The outer end of this rod is threaded to receive a nut 20 between which and the enlarged portion of the T-member 13 a coil spring 21 surrounds the rod. (See Figures 4 and 6).

Telescopically secured to the opposite end of the rod 19 is a sleeve 22 formed with a longitudinal slot 23 to receive a pin 24 carried by the rod 19. At its outer end this sleeve is formed with an annular shoulder 25 in front of which it is threaded to receive a nut 26 similar to the nut 20. The thread on the rod 19 is right hand, whereas the thread on the sleeve 22 is left hand. Between the nut 26 and the T-member 13 a coil spring 27 surrounds both the sleeve 22 and the rod 19. (See Figures 4 and 6).

Provided on the right-hand side of the cross portion 14 of the T-member 13, near its vertical part 16, is a depending boss 28 to which a bell crank lever 29 is secured by a pivot pin 30. The outer end of the horizontal portion of this bell crank lever is connected by a link 31 to one end 11 of the floating member 12. The vertical part of the bell crank lever 29 terminates at its lower end in a wide yoke 32 that is pivotally secured to the ends of a horizontal U-piece 33 which encompasses the rear end of the spring 21 and the nut 20, to engage its closed end with an annular shoulder 34 on the rod 19. (See Figures 4, 5 and 6).

The weight of the occupant of the chair, and more particularly when one assumes a reclining position therein, will urge the member 12 outwardly to pull the U-piece 33 against the shoulder 34 and thereby move the rod 19 in the direction of the sleeve side of the vertical portion 16 of the T-member 13. The nut 20, threaded on the rod, will then be forced against the spring 21 to compress it for the purpose of yieldingly supporting a part of the weight of the occupant of the chair. The remaining portion of this load is carried by the other spring 27 when simultaneously engaged by the nut 26 on the sleeve 22 which has a sliding fit on the other end of the rod 19.

The sleeve 22 is moved along the rod toward the vertical part 16 of the T-member 13, by the engagement of a horizontal U-piece 35 with the shoulder 25, said U-piece being pivotally connected to the yoke portion of a bell crank lever 36 similar to the bell crank lever 29. This lever, which is pivotally secured to a depending boss 37 on the T-member 13, is pivotally connected at its outer end by a link 38, to the end 11 of the floating member 12.

For the purpose of adjusting the tension of the springs 21 and 27 to accommodate occupants of different weights, so that both light and heavy persons may rest and relax comfortably in the chair, I have provided the following means. Attached to the outer end of the rod 19 is an adjusting knob 39 which may be turned to advance the nuts 20 and 26 for the purpose of increasing the tension of the springs 21 and 27 respectively, or to reverse the movement of the nuts to relax the tension of those springs without changing the position of the lever centers. Deep recesses are formed in the outer face portions of the nuts to permit them to be moved outwardly a substantial distance over the shoulders 34 and 25 before being stopped by them.

When the occupant of the chair assumes a reclining position, the yoke 11 on the lower end 75 of the T-member 13 engages the member 12 to

assist in swinging the whole spring-actuating assembly for the purpose of making its floating qualities completely available to the occupant. Whether one assumes a sitting or a reclining position in the chair, the springs 21 and 27 will be placed under sufficient tension by the floating member 12 to permit the occupant to float on them at all times. The outward movement of the tubular member 12, in response to a similar movement of the lower ends of the lever member 10 8, draw the outer ends of the bell crank levers 29 and 36 downwardly by means of the connecting links 31 and 38 to compress these springs, which are pre-adjusted to floatingly carry an easy and restful manner a person of light, medium or heavy weight.

In Figure 8 I have shown the position of the seat and back members of my chair when occupied by a light person, whereas in Figure 7 I have shown the chair occupied by a person 20 whose weight is substantially fifty pounds more than that of the occupant of the chair in Figure 8. It will be observed that in each instance the seat and back members automatically accommodate themselves to the body of the occupant 25 of the chair irrespective of the weight of that occupant. Nor does the upright or an intermediate position of the occupant of the chair affect the automatic adjustment of its back and seat to his or her body.

The spring mechanism just described is concealed from view by a shield board 40 attached to the front edges of the lower ends of the swinging members 8, 8, and by triangular side boards 41 secured to the sides of said members.

The forward movement of the upper portion of the lever members 8, 8 is limited by their engagement with the upper front edges of the slots in the seat members 5, 5 through which they project. The upper ends of the side boards 41 have recessed portions 42 for engagement with the fixed rod 10 to limit the upward movement of the seat.

Secured to the base rails 4, 4 are channel guides 44 which receive longitudinal members 45 that have attached to their outer ends posts 46. These posts are held in upright positions by curved reinforcing blocks 47 attached to the slidable members. Hingedly secured to the upper ends of the posts 46 is a foot rest 48 carrying a cushion 49, and adapted to be held in a horizontal position by a breakable link 50. When the foot rest is not used, it may be folded up and slid under the front portion of the chair.

While I show a connected foot rest in Figures 2 and 3, a detachable foot rest such as the foot rest 51 illustrated in Figure 8, may be employed if desired.

Having described my invention, I claim:

1. A chair of the type described, comprising a base, a seat pivotally secured at its front end to said base, a back pivotally attached to said seat, vertical members fulcrumed at their middle portions to said seat, arms pivotally joined at their rear ends to said back and at their forward ends to the upper ends of said vertical members, and yielding means connected between the lower ends of the vertical members and the base to floatingly support the seat and back in an upright or a reclining position.

2. A chair of the type described, comprising a base, front legs for said base, projecting above the latter, a seat pivotally secured at its front end to the upper ends of said front legs, a back 75
